Dec. 340

Charles A. Lambard of Augusta, Me.
Letters Patent No 340. Dated Dec 10th 1850.

The schedule referred to in these Letters Patent and making part of the same.

To all whom it may concern:

Be it known that I Charles A. Lambard of the City of Augusta & State of Maine, have produced a new ornamental design for an air light cooking Stove which Stove I call the Kennebec Air light Stove. — And I do hereby declare that the accompanying & annexed drawing is a full and accurate delineation of a stove constructed after my design — The sides not represented in the drawing being similar to & symmetrical with that represented, & the back of the stove having no peculiar distinguishing ornament.

What I claim as my production and desire to secure by letters patent, is the combination and arrangement of ornamental figures & forms represented in the accompanying drawing, as making an ornamental design for an air light Cooking Stove.
